UNITED STATES PATENT OFFICE.

ROLLYN H. BAKER, OF DAYTON, OHIO, ASSIGNOR TO THE BAKER MANUFACTURING COMPANY, OF DAYTON, OHIO, A CORPORATION OF OHIO.

METHOD AND APPARATUS FOR DISPENSING ICE-CREAM CONES.

Application filed November 1, 1924. Serial No. 747,278.

My present invention relates to devices to use in refreshment establishments and the like for storing and dispensing ice cream cones one at a time. In places of this kind it is desirable to have cones available instantly when they are called for, and yet there is a great and growing distaste for having them out in the open where they can catch dust and are subject to contamination by flies. Various forms of containers have been devised, but in all of these in addition to slowing down the service there is the added objection that the clerk must reach into the container and remove the cones with his hand. This is regarded as particularly objectionable.

To overcome this objection I have devised a container consisting of a tubular glass magazine having at its lower end a mechanism adapted to let the cones out, or eject them, one at a time. In some respects it resembles the well-known containers for dispensing paper cups. To avoid having to handle the cones I provide a conical receptacle which the clerk holds at the mouth of the tube through which the cones emerge from the container. The cone drops into this receptacle and remains therein while the clerk fills it with ice cream. The clerk then extends his hand toward the customer, who with his own hand lifts the cone from the receptacle. When not in use the receptacle may stand inverted on a plate or some other clean surface. The large manufacturers of ice cream cones now use automatic machines wherein batter poured into a tank is molded into cones, which are baked and discharged from the ovens, all automatically, and they emerge from the machine nested ready to slip into paper tubes, these tubes then being packed in cartons. The entire process is mechanical and the cones are not touched by hands before they reach the retail dealer. Therefore, with my improved container and novel method of handling the cones, it is possible, and quite practicable, for the customer's hand to be the first which has ever touched the cone he eats. Where the cones are in tubes, as above mentioned, it is quite easy to drop them out of the tube directly into the magazine without touching hand to them. In cases where two or more customers are to be served with cones at a table or elsewhere, a plurality of receptacles may be used, and as the cones they contain are filled these receptacles may be set in sockets in a special tray. Then the customers may

lift their cones out of the receptacles, leaving the latter standing in the tray. In another form of tray the separate holders are dispensed with.

I shall now describe one embodiment of my invention, referring to the accompanying drawing, in which,

Fig. 1 is a side elevation of the apparatus, portions being removed to display other parts;

Fig. 2 is a plan view with the magazine removed, the view being taken on the line 2—2 of Fig. 1;

Fig. 3 is a fragmental view of part of the mechanism, seen from the interior of the device and looking toward the front;

Fig. 4 is a view showing the receptacle held by the clerk for the cone emerging from the container;

Fig. 5 shows a modification in the discharge tube; and

Fig. 6 shows a tray for filling and serving cones.

The various parts of the apparatus are attached to or otherwise supported by a base 10, having a clamp 11 by which to secure the base to a counter or other suitable support. The base 10 is in fact a ring, and a tube 12 fitted into this ring extends downward to form a shield or hood for the lowermost cone in the container. Pivotaly attached to the base 10 are two pairs of horizontally extending arms 13, the pivotal center, the screw 14, being at one side of the hole in the base. One pair of these arms lies flat on the base, and extending around the hole to the opposite side each arm terminates in an oblique, upwardly extending cam 17. These cams are in apposition and diverge as they extend upward. A sleeve 15 surrounding the screw 14 rests on the arms, one of which arms is offset to permit it to lie on top of the other arm where they overlap, while the remainder of this arm lies flat on the base in the same plane with the other arm. The second pair of arms 13, which is a duplicate of the first, is confined between the upper end of the sleeve 15 and a cover plate 16, the head of the screw 14 being on top of this cover plate. While these upper arms are like the lower ones, they are inverted, so the cams 17 depend. These apposed cam-like terminals of the arms, and their relative positions, are well shown in Fig. 3. The front portion of the cover plate is secured to the base 10 by screws 18 and in-

terposed sleeves 19. The arms of the respective pairs are moved toward each other by springs 20 wound around the sleeve 15, with their ends anchored to the arms, as at 21. At 5 22 a slender stud set in the base serves as a stop, limiting the inward movement of the arms, also centering the arms with reference to the tube 12 depending from the base. A lever 25 is pivotally mounted on the base, 10 with one end extending through a slot 26 in the front of the hood 35, and arranged to rock on a fulcrum 27. The inner end 28 of this lever plays between the cams 17 on the arms. When the lever is pressed downward the end 15 28 rises and entering between the cams 17 spreads the upper arms. When the lever is raised the end 28 moves between the cams 17 of the lower arms and spreads these arms. The lever passes through a neutral position, 20 in which neither pair of arms is spread, in moving from one pair of arms to the other. See Fig. 3.

The arms 13 are adapted when moved by their springs to embrace an ice cream cone 25 at a point near its upper edge, and because of its conicity the arms afford ample support not only for one but for a stack of cones. The distance between the upper and lower arms is such that when the bottom cone in a 30 stack is in the embrace of the lower arms the upper arms are at the proper altitude to close in on the exposed portion of the next cone above.

Before describing more of the structure I 35 shall briefly explain the operation of the portions already described. In Fig. 1 the end 28 of the operating lever is wedged in between the apposed ends of the upper arms, the arms being therefore open. The stack of cones, indicated with dotted lines, is supported by the lower arms which embrace the bottom cone. Lifting the lever 25 will remove the inner end 28 of the lever, which I 40 shall hereinafter refer to as the pusher, from between the upper arms and allow these arms to embrace the second cone in the stack, the spring 20 moving the arms thus. Moreover, by referring to Fig. 3 it will be seen that the upper arms are permitted by the pusher 45 to embrace the second cone before the pusher engages the cams 17 of the lower arms. Continuing its descent, the pusher engages the lower cams, and because of their obliquity it moves the lower arms apart. The duty of 50 supporting the stack now devolves upon the upper arms, but the bottom cone is left without support and may now drop by gravity through the tube 12 into the portable receptacle held by the operator at the lower end of the tube. It sometimes happens, however, 55 that the bottom cone adheres to the cone above it, and by referring to Fig. 1 it will be seen that in its descent the end of the pusher will impinge upon the edge of the cone, in 60 case it fails to drop by gravity, and push it off

of the cone above. The parts are so proportioned and positioned, relatively, that the arms move apart sufficiently ahead of the cone as it is pushed down, to avoid any conflict or possible injury to the cone. Having ejected 70 the bottom cone the operator next moves the lever 25 downward. This withdraws the pusher from between the lower arms and allows them to spring together. Continued downward movement of the lever causes the 75 spread of the upper arms, when the stack of cones drops until arrested by the bottom cone seating itself in the embrace of the lower arms. Thus a cycle is completed and everything is again as in Fig. 1 except that there 80 is one cone less in the stack. It is immaterial whether the lever is left in its upper or lower position between sales, as it requires an upward and a downward movement of the lever to eject each cone. 85

The operative parts are covered by the hood 35, which hood terminates in a collar 36, forming a socket to receive the lower end of the glass magazine 37. For the purpose of guiding the cones to the arms 13 a tubular member 38 is secured in the lower end of the collar 36 and extends down to the lower arms, thus holding the arms down although allowing them sufficient freedom. The portions of the arms that actually embrace the cones are 90 made to project inward from the bodies of the arms, as at 39—39—39—39, Fig. 2. Slots 40 are cut in the tube 38, through which the 95 projections 39 of the upper arms extend. These slots also serve as guides for the upper arms and prevent their falling away from the cover plate 16. 100

While my invention has some of the characteristics of the well known machines for dispensing paper cups, the conditions surrounding the dispensation of cones and cups are different in many respects. One difference is that while only the rim of the cup comes in contact with a person's lips, the receiver of a cone eats it entirely. Moreover, 110 the cup is usually removed from the container by the person who is to drink from it, while the cone is always handled by another before the person who is to eat it takes it into his own hand. Ice cream cones are crisp and brittle, especially when quite fresh. Moreover, they vary some in size. My spring actuated arms accommodate themselves to these variations and there is no danger of crushing the cones, such as there might be if the 115 supporting arms were positively drawn in to a predetermined point each time, as the supporting devices are in many of the cup dispensers. Another difference is the relatively long distance from edge to edge of the cones in a stack. On the other hand, their pronounced conicity enables cones to be separated very readily, even when they adhere, because the moment the adhesion is overcome 120 the cones become quite free. This makes it 125 130

feasible to positively separate adhering cones by pressure on one side of the edge. Cones usually adhere so little that no difficulty is experienced from the tendency to rock the 5 stack arising from pressing on one side only of the adhering cone. But to overcome any possible trouble from this source the tube 12 may be set so it inclines forward, as in Fig. 4. As is there shown with dotted lines the lower 10 end of the bottom cone hangs close to the rear wall of the tube, or actually touches it, and prevents the cone rocking when the pusher bears down on the front edge of the cone.

In Fig. 4 a holder for cones is shown with 15 a cone in it. Fig. 5 shows the tray previously referred to, consisting of a plate 45, having a plurality of openings surrounded by depending frusto-conical flanges 46. With dotted lines a cone is shown resting in one of these 20 openings. The plate is provided with legs 47 and a handle 48. A convenient form for this tray is rectangular, with two rows of three sockets each. The clerk may drop one or more cones directly from the container into 25 these sockets, and standing the tray on the counter or other flat surface he has both hands free for filling the cones with ice cream. The flanges 46 afford lateral support for the cones and keep them from tipping or being 30 unsteady while ice cream is being put into them. This is a convenient way of serving cones at the tables in an ice cream parlor or to the occupants of an automobile. While the single holder shown in Fig. 4 is more convenient when a single cone is being served, 35 the tray is better for serving two or more cones at a time.

In practice the arms 13 are punched out of 40 sheet metal, although they may be made in other ways if desired. When made of sheet metal the ends are bent upward to form the 45 cams 17. As the outside of the bend assumes a rounded contour the most prominent part of the bend is naturally removed a short distance from the surface of the base, or of the 50 cover plate. By making the pusher thin enough so it passes beyond these prominent parts of the bends, the arms are enabled to grip the pusher slightly and tend to retain 55 the operating lever in its upper or lower position, as the case may be. This is not an essential feature, but a convenience. While in the present case I have pivoted all of the arms on a single axis, one upper and one 60 lower arm might be mounted on one axis and the other two arms mounted on another axis, these axes being more or less adjacent to each other. This, or any other substantially equivalent arrangement of mounting the arms, is 65 within the scope of my invention. Moreover, 70 separate springs may be used for the several arms, or a different kind of springs. Other equivalent mechanical arrangements whereby the broad objects of my apparatus may be

effected are to be understood as within the 65 scope of my invention.

What I claim as my invention and desire to protect by Letters Patent, is as follows:

1. In a device for dispensing ice cream cones, a base, a pair of cone supporting members mounted thereon, adapted to be moved toward each other to engage the exposed part of one cone in a nested stack of cones and assume the support thereof; springs whereby said members are so moved, a manually operable member whereby to separate said supporting members and allow said cone to drop, and means for arresting said dropping cone at a point which brings the next cone in the 75 stack into position to receive similar support when said supporting members are again subjected to the action of said springs.

2. In a device for dispensing ice cream cones, a base, a pair of cone supporting members mounted thereon, adapted to be moved toward each other to engage the exposed part of one cone in a nested stack of cones and assume the support thereof; means for so moving said members, a manually operable member whereby to separate said supporting members, allowing the supported cone to drop, means for arresting the dropping cone at a point which brings the next cone into 80 position to receive support from said supporting members, means actuated by said manual member for releasing the bottom cone from said arresting means after the first mentioned members have assumed support of the next cone above, and means actuated by said manual member for pushing the bottom cone 85 off of the supported cone after the former is released from said arresting means.

3. In a device for dispensing ice cream cones, a base, a pair of semi-circular arms pivotally attached thereto and to each other, with their free ends apposed, said arms being adapted to move toward each other and embrace the exposed part of one cone in a nested stack of cones, thereby supporting the embraced cone and those above it, springs for moving said arms toward each other, and a lever mounted on said base in proximity to said apposed ends, adapted to wedge between the ends and spread the arms to release a cone held by them, said lever being adapted, 105 when not holding the arms apart to impinge on the rim of a cone which has adhered to the cone supported by the arms and push it therefrom.

4. In a device for dispensing ice cream 110 cones, a base, a pair of semi-circular arms pivotally attached thereto and to each other, with their free ends apposed, said arms being adapted to move toward each other and embrace the exposed part of one cone in a nested 115 stack of cones, springs for causing the arms to so act, a sub-support for the bottom cone in the stack, whereby the stack is maintained at 120 125

an altitude enabling said arms to embrace the next to the bottom cone as aforesaid, a manually operable member adapted to separate the arms sufficiently to release the cone it is supporting, and to remove said sub-support, means preventing said manually operable member from separating the arms except when the sub-support is in effective position, and from removing the sub-support except 10 when the arms are free to embrace a cone, and a pusher whereby as said sub-support is removed the bottom cone is pushed off of the next cone if it fails to drop by gravity.

5. In a device for dispensing ice cream cones one by one from a vertical stack of cones, a base, a pair of arms pivotally attached to said base at one side of the stack of cones, said arms extending toward the other side of the stack and being adapted to 20 move toward each other and embrace the exposed portion of an intermediate cone and support it together with the cones thereabove, a sub-support adapted to support the bottom cone at an altitude to bring the next cone 25 above into position to be embraced by said arms; a manual operating member whereby to spread said arms and release a cone therefrom, and to remove said sub-support from its supporting position, and means whereby 30 said arms are made to embrace the second cone before the sub-support is removed from the bottom cone, and whereby the sub-support is put into supporting position before said cone is released from the arms.

35. 6. In a device for dispensing ice cream cones one by one from a vertical stack of cones, a base, a pair of arms pivotally attached to said base at one side of the stack of cones, said arms extending toward the 40 other side of the stack and being adapted to move toward each other and embrace the exposed portion of an intermediate cone and support it together with the cones thereabove, a sub-support adapted to support the bottom 45 cone at an altitude to bring the next cone above into position to be embraced by said arms; a manual operating member whereby to spread said arms and release a cone therefrom, and to remove said sub-support from its supporting position, means whereby said 50 arms are made to embrace the second cone before the sub-support is removed from the bottom cone, and whereby the sub-support is put into supporting position before said cone is released from the arms, and a pusher operated by said manual member whereby as said member removes the sub-support from the bottom cone said cone is pushed off of the next cone.

60. 7. In a device for dispensing ice cream cones one at a time from a nested stack of cones, two pairs of arms pivotally mounted on a base at one side of the stack, one pair above the other, said arms extending approxi-

mately half way around the cones with the 65 free ends of each pair brought into apposition on the opposite side of the stack, each pair of free ends being provided with oppositely inclined cams which diverge in the direction of the other pair; springs adapted 70 to move the arms of each pair toward each other, enabling each pair of arms to embrace a cone and support it, and a lever fulcrumed in a plane intermediate said pairs of arms and adapted to enter between the cam faces of either pair, according to which way the lever is rocked on its fulcrum, and cam the arms apart, the distance between the upper and lower arms being substantially equal to the distance from the top of one cone to the 80 top of the next cone in the stack.

8. In a device for dispensing ice cream cones one at a time from a nested stack of cones, two pairs of arms pivotally mounted on a base at one side of the stack, one pair 85 above the other, said arms extending approximately half way around the cones with the free ends of each pair brought into apposition on the opposite side of the stack, each pair of free ends being provided with oppositely inclined cams which diverge in the direction of the other pair; springs adapted to move the arms of each pair toward each other, enabling each pair of arms to embrace a cone and support it, and a lever fulcrumed in a plane intermediate said pairs of arms and adapted to enter between the cam faces of either pair, according to which way the lever is rocked on its fulcrum, and cam the arms apart, the distance between the upper and lower arms being substantially equal to the distance from the top of one cone to the top of the next cone in the stack, the lever being 90 adapted to impinge on the bottom cone as it separates the lower arms and push the cone off if it tends to adhere to the second cone.

9. In a device for dispensing ice cream cones, a base, means carried thereby for supporting the second cone in the stack, a pusher adapted to impinge on the rim of the bottom cone and push it off of the cone above, and a member supported by the base for the lower end of the cone to lie against to balance the cone, so the pressure of the pusher on one side will not rock the cone from its normal 105 position.

10. In a device for dispensing ice cream cones, means for supporting the second cone in the stack, a pusher adapted to impinge on the rim of the bottom cone and push it off of the cone above, and a tube surrounding the lower end of the bottom cone, through which the cone drops, said tube inclining toward the side of the cone on which the pusher acts so the lower end of the cone will nearly touch the interior of the tube while the pusher pushes the cone off.

ROLLYN H. BAKER.
